D. H. WILGUS AND S. M. DENNY, OF HARVEYSBURG, OHIO.

Letters Patent No. 92,500, dated July 13, 1869.

IMPROVEMENT IN HARVESTERS.

The Schedule referred to in these Letters Patent and making part of the same.

To all whom it may concern:

Be it known that we, D. H. WILGUS and S. M. DENNY, of Harveysburg, in the county of Warren, in the State of Ohio, have invented certain new and useful Improvements in Reaping-Machines; and we do hereby declare that the following is a full and exact description thereof, reference being had to the accompanying drawings, and to the letters of reference marked thereon.

In the following description, we shall denominate that side of the machine which will occupy a position next to the standing grain the outer side, and that side next to the stubble the inner side of the machine.

Figure 1 represents a side elevation of the inner side of the machine.

Figure 2 represents a plan view of the machine, with a portion of the platform broken away, to exhibit the gearing, &c.

Figure 3 represents a portion of the driver's platform, the shipping-lever, treadle-lever, and shipping-rod.

Our invention relates to a new and simple arrangement of mechanism for receiving and depositing the gavel, which will be fully explained herein.

The two driving-wheels, A B, are securely fixed to their axle, upon which the large gear-wheel C is also secured, and these three wheels and their axle revolve together.

The driver's platform, D, rests upon the axle of wheels A B, suitable boxes being provided, under the platform D, to receive the axle.

Also, underneath this platform, there are suitable boxes, for supporting shaft a, which is provided with the loose pinion b and clutch c.

The rear end of shaft a extends outward beyond platform D, and is furnished with a pulley, d, which receives band e.

The latter also passes around pulley f, on the front end of roller g.

The clutch-shipping lever h is pivoted underneath the platform D.

One end of lever h is provided with a groove, which embraces the rim i, which is attached to movable portion of clutch c, and the other end of lever h is provided with a hole, through which the bent rod j will pass freely.

The shipping-rod j is connected to treadle-lever E, by means of an eye-bolt, as represented in fig. 3.

There is a block, k, connected with a portion of the frame, under platform D, having a suitable hole through it, for the shipping-rod j to work, when caused to move up and down by the treadle-lever E, to which it is connected.

The grain-platform is secured, in the usual manner, to the rear of the driver's platform.

Two arms, l m, support the shaft n, to which the curved fingers o are attached.

p is an arm, passing through a slot, q, in the end of treadle-lever E; and as this rod or arm p is secured to shaft n, the movement of the treadle-lever E actuates the gavel-deliverer M.

The endless apron H surrounds the grain-platform, and at each end thereof there is a roller, g, which supports the endless apron H, as represented in fig. 2.

These rollers g are journaled in the frame L X.

By the progressive movement of the machine, the driving and supporting-wheels A B, will cause the gear-wheel C to drive pinion b, and the movable part of clutch c being in contact with that part of the clutch fastened to pinion b, the shaft a will be revolved, and the pulley d, upon its end, will, through belt e, drive the endless apron upon rollers g, in the direction indicated by arrows x x.

The fingers o o, of deliverer M, occupy the position represented in fig. 2, while receiving a gavel, which is discharged, by the endless apron H, upon the fingers o o of the deliverer M.

As soon as a proper quantity of grain is thus received upon the fingers o o to make a gavel, the driver will place his foot upon the front end of lever E, and depress it, causing its rear end to be elevated, and, through arm p, a partial rotation is given to shaft n, which will carry with it its fingers o, and discharge the gavel upon the ground in the rear of the driver's platform.

At the same time that the treadle-lever E causes the discharge of the gavel, as above described, it will draw the bent rod j through the hole in the end of shipper h, and the form of this rod is such that it, in passing through the shipper h, will move it laterally upon its pivot, and thereby throw the clutch c out of connection, and thus stop the action of shaft a, and band e, and cause the endless apron H to rest, while each gavel is being discharged from deliverer M upon the ground, and until the deliverer returns to the position shown in fig. 2.

The dotted lines o' o', in fig. 1, represent the position of the fingers when delivering a gavel.

It will be understood, from the foregoing description, that the gavel-deliverer M is at rest while the endless apron H, which receives the cut grain, is in motion, to convey the grain to the deliverer, and that the apron H will remain at rest while the deliverer M discharges its gavel and returns to receive another.

A suitable shelf may be employed to aid the apron H to deliver its load of grain upon the deliverer's fingers.

A simple shaft, with two arms standing at right angles thereto, may be employed, instead of the bent rod j, for actuating the shipper h.

It should not be omitted herein to state that there are two supports, F, upon platform D, in which the bolt rests, upon which the treadle-lever E is supported and oscillates, as it is actuated by the driver, for the purposes described.

Having fully described our invention, What we claim, and desire to secure by Letters Patent, is—

The treadle-lever E, arm p, rod j, shipper h, and

clutch c, arranged and operating in combination with deliverer M and apron H, substantially as and for the purpose described.

D. H. WILGUS.
S. M. DENNY.
